UNITED STATES PATENT OFFICE.

WALTER L. CULVER, OF ST. LOUIS, MISSOURI, ASSIGNOR TO THE WROUGHT IRON RANGE COMPANY, OF SAME PLACE.

WATER-BACK FOR RANGES OR STOVES.

SPECIFICATION forming part of Letters Patent No. 653,949, dated July 17, 1900.

Application filed February 5, 1900. Serial No. 4,098. (No model.)

To all whom it may concern:

Be it known that I, WALTER L. CULVER, of the city of St. Louis, State of Missouri, have invented certain new and useful Improvements in Water-Backs for Ranges or Stoves, of which the following is a full, clear, and exact description, reference being had to the accompanying drawings, forming a part hereof.

This invention relates to water-backs for ranges and stoves; and it consists of the novel construction, combination, and arrangement of parts hereinafter shown, described, and claimed.

The object of this invention is to provide an improved water-back for ranges by means of which the noise which is usually incident to heating water by water-backs of the usual construction is obviated, while at the same time the water to be heated is circulated more freely and rapidly over the heating-surface.

In the drawings, Figure 1 is a view showing my improved water-back in use, the range and the water-reservoir being in section. Fig. 2 is a vertical sectional view taken through the center. Fig. 3 is a view in perspective showing the device in detail.

Referring by numerals to the accompanying drawings, 1 indicates the end or base of the water-back, integral with which are the sides, top, and bottom. The top 2 occupies a horizontal plane when in use and is provided with an integral flange or seat 3 near its rear end and at a suitable distance from the end or base 1 and with a rounded flange or nut-seat 4 near its forward end. The sides 5 are also integral with the end or base 1 and with the top 2, and each is provided with a suitable projection 6, the same in continuation of the flange 3. The inclined bottom 7, like the top and sides, is cast integral with the back and with the sides and is provided with an integral flange or seat 8 in alinement with the flange 3 and projection 6. The said sides, top, and bottom converge at their forward end and form an integral threaded projection 8^a. The base or end 1 is provided with an integral apertured ear 9, the same being in alinement with the flanges 3 and 8 and with the projection 6, all of which are adapted to

rest against the interior of the stove 10 when 50 the device is in use.

When the device is applied, it is placed within the fireplace in the range and projected laterally through an aperture until the flanges 3, 6, and 8 rest against the interior of 55 the range. When so applied the base or end 1 is held in alinement with the lining of the range, and the receptacle formed by the sides, top, and bottom projects laterally and is connected to the reservoir or water-receptacle 60 10^a by projecting the threaded projection 8 through an aperture in the said receptacle and applying a nut 11 to the said projection. Before so adjusting the parts the gum washer 12 is placed over the threaded projection and 65 forms a very close connection with the water-receptacle, so that none of the water may escape around the projection, and thereby cause inconvenience.

It will be noticed from the drawings and 70 description that one of the main and essential features of my invention is in constructing a water-back provided on its top interior surface with a smooth and unobstructed surface, so that the rise and expansion of the 75 water and steam when heated may pass unobstructed over a smooth surface, and the same not being resisted in any manner absolutely prevents any gurgling or bubbling of the water in the water-tank.

A water-back constructed in accordance with the above principles possesses superior advantages over all others and effectually overcomes all objections which have heretofore been urged against devices of this class. 85 By this improved construction, wherein a horizontal unobstructed top wall is presented for the passage of the heated particles and the lower wall is inclined downwardly in the direction of the heat-absorbing surface the 90 water is allowed to circulate freely into and out of the device and no unpleasant noise is created thereby. By this form of the device a greater heat-absorbing surface is presented to the action of the fire; also, the cooler water 95 is permitted to gravitate to the lowest point of the said heat-absorbing surface and rises along with the same while being heated and

to escape into the tank without materially interfering with the inflowing current. No steam is allowed to congregate in the top and the noise incident to its escape is obviated.

5 In all these and in other respects the device presents improvements over the ordinary construction and the cost involved in its construction or manufacture is not great.

I claim—

- 10 1. The herein-described water-back, comprising a casting having a base or end, a horizontal unobstructed top, vertical sides, a bottom inclined downwardly in the direction of the heat-absorbing surface, and a tubular projection integral with the said sides, top and bottom, the said tubular projection being in horizontal alinement with the said top, substantially as specified.
- 15 2. The herein-described water-back, comprising a casting having a base or end, a horizontal unobstructed top, vertical sides, a bottom inclined downwardly in the direction of the heat-absorbing surface, flanges integral with the said sides, top and bottom for holding the said base a suitable distance from the side of the range, a tubular projection integral with the said sides, top and bottom in horizontal alinement with the top and devoid of internal projections, and a means for

connecting the said tubular projection with the water-receptacle, substantially as specified.

3. As an article of manufacture, a water-back for ranges provided with suitable flanges for attaching it to the range, a screw-threaded 35 nipple for attaching the water-tank to the water-back, said water-back having a bottom wall inclined downwardly in the direction of the heat-absorbing surface, a smooth and unobstructed interior surface at its top, substantially as specified.

4. As an article of manufacture, a water-back for ranges provided with a base or end having integrally formed therewith suitable flanges for attachment to the range, a top wall 45 projecting horizontally and at right angles to said fire-surface wall and having its interior surface smooth and unobstructed, the lower wall projecting upward at an acute angle from said base or end, and a screw-threaded nipple 50 formed integral with said walls, substantially as specified.

In testimony whereof I affix my signature in presence of two witnesses.

WALTER L. CULVER.
